DEFERRED-ACTION BATTERY DIAPHRAGM-
RUPTURING DEVICE

Charles M. Gold, Franklin Square, N.Y., assignor to
Yardney International Corp., New York, N.Y., a corpora-
tion of New York

Filed Jan. 26, 1960, Ser. No. 4,806
5 Claims. (Cl. 136—90)

The present invention relates to a device for rupturing a diaphragm for the purpose of enabling the passage of a fluid, especially a liquid, through an initially sealed duct. Such devices are used, for example, in a reserve-type or deferred-action electric battery in which one or more electrochemical cells in the dry-charged state are activated, in response to a predetermined signal, by the transfer of electrolyte liquor from a storage container to the housing of each cell.

Heretofore, diaphragms for the purpose set forth have generally been made of easily frangible material, such as a plastic or ceramic substance, adapted to be ruptured or shattered on contact with a pointed or even a blunt piercing member. A disadvantage of such systems is that, notwithstanding the provision of various safeguards, premature activation sometimes occurs on account of acceleration, impact or vibration whereby the diaphragm is urged against the piercing member, or vice versa, with sufficient force to cause rupture of the former by the latter.

It is, therefore, an object of the present invention to provide an improved combination of diaphragm and piercing device which affords the necessary safeguards against undesired activation of such device.

A more specific object of this invention is to provide means for quickly and effectively rupturing, in response to a predetermined signal, a sheet-metal diaphragm barring the flow of a fluid such as, for example, a liquid electrolyte.

It is also an object of the invention to provide a piercing device of the character referred to which can be readily activated by a mechanism adapted to perform a concurrent operation in response to the same signal, such as the release of a charge of compressed gas serving to exert pressure upon the liquid to be driven past the ruptured diaphragm.

The invention resides, according to one of its aspects, in the positioning of a generally triangular cutter, having a knife point at the acute apex of the triangle, adjacent a metallic diaphragm, in combination with means for pivoting the triangle about its base in a sense driving the knife point into the diaphragm whereby the latter is cut open by an action comparable to that of a can opener upon the flat end of a tin can.

In accordance with a more specific feature of the invention, the generally triangular cutter forms one arm of a bell-crank lever whose other arm is disposed adjacent an operating member poised to exert upon this latter arm, in response to an activating signal, sufficient pressure to swing the bell-crank lever about its pivot in a diaphragm-piercing sense. The operating member may be a piston adapted to be driven toward the adjacent lever arm by, for example, the detonation of an explosive charge.

The invention will be described in greater detail with reference to the accompanying drawing wherein:

FIG. 1 shows, in longitudinal section, an activator for a dry-charged electric battery, the activator incorporating a diaphragm-piercing mechanism according to the invention.

FIG. 2 shows parts of the diaphragm-piercing mechanism in perspective view; and

FIG. 3 shows, again in perspective view, another part

2

of the activator adapted to be operated simultaneously with the diaphragm-piercing mechanism.

The activator shown in the drawing comprises a cylindrical container 10 for a liquid electrolyte, e.g. a concentrated aqueous solution of potassium hydroxide, this container having a large outlet 11 initially blocked by a metallic diaphragm 12. A shield 13, in the form of a perforated cap, overlies the outlet 11 on the inside of the container. This outlet leads to a chamber 14 within which a bell-crank lever 15, consisting of two arms 15a and 15b, is pivotable about a transverse pin 16. Arm 15a rests horizontally on a safety stud 17 which prevents the cutter 15 from striking the diaphragm and weakening it before activation; the slightly curved arm 15b depends approximately vertically adjacent diaphragm 12 and is of generally triangular configuration, the base of the triangle being in the vicinity of pin 16 while its apex, forming a knife point 15c, is turned toward the diaphragm. It will be noted that the height of the triangle, as measured between point 15c and pin 16, is substantially less than the spacing of the pin from diaphragm 12.

The container 10 is further provided, opposite outlet 11, with a gas-inlet tube 18 terminating in a nipple 19 which is initially sealed by a tubulation 20 having a constricted neck 20'. A bail 21 of spring wire, biased for counter-clockwise rotation as viewed in FIG. 1, is wound about a pin 22 which bridges a pair of brackets 23a, 23b on a supporting plate 24. This plate carries a pair of terminal posts 25a, 25b which are connected by a pair of conductors 26a, 26b across a source of current 27 (here shown diagrammatically as a battery) via a normally open switch 28. A fusible wire 29 is tied electrically and mechanically to the posts 25a, 25b and is stretched in a loop around a lug 30' of a detent element 30 which is pivotable about a pin 31 and has a shoulder 30" engaging the bail 21 to latch it in its illustrated position. Tube 18 extends from a cartridge 32 containing a compressed gas.

The elements supported on plate 24 and illustrated in FIG. 3, forming part of a gas-release mechanism, are enclosed within a shell 33 provided with a gas passage 33'. A bladder 34, clamped between plate 24 and a wall of container 10, surrounds the shell 33 and extends longitudinally within the container toward the outlet 11 thereof. This bladder, originally deflated, is inflatable by the pressure of gas from cartridge 32, after the activation of the release mechanism in a manner to be described, to exert pressure upon the surrounding electrolyte liquid and to force it outwardly through the simultaneously unblocked outlet 11.

Chamber 14 is provided at one end with a discharge tube 35 for the electrolyte, leading to the cells of a dry-charged electric battery not shown. Opposite tube 35, a plug 36 extends into chamber 14; this plug houses a slideable piston 37, bearing upon the lever arm 15a, and a squib 38 whose explosive charge is adapted to be set off by battery 27 via conductors 26a, 26b' upon closure of switch 28.

In operation, the activator shown in the drawing is connected by its discharge tube 35 to the battery to be served thereby. When, thereafter, the switch 28 is closed, current from source 27 detonates the charge of squib 38 to drive the piston 37 downwardly; this action causes the safety stud, which may be of soft metal such as copper to yield (dot-dash lines, FIG. 1) as the lever 15 swings counterclockwise about its pivot 16 so that point 15c slits the diaphragm 12 from the bottom up. At the same time the current flowing through conductors 26a, 26b melts the wire 29, thus releasing the detent 30 and unblocking the nipple 19 so that gas from cartridge 32 streams through tube 18 into bladder 34 to inflate it. The pressure of the bladder upon the electrolyte in container

10 forces this liquid through the cut in diaphragm 12 and thence through chamber 14 into discharge tube 35 from which it enters the associated battery casing. It will be understood that the rush of liquid also widens the rupture in diaphragm 12 made by the cutting arm 15b of lever 15. Shield 13 keeps the bladder 34 out of contact with the jagged edge of the cut, and with point 15b, to prevent its destruction and to hold the gas confined therein.

The invention is, of course, not limited to the specific embodiment described and illustrated but may be realized in various modifications and adaptations without departing from the spirit and scope of the appended claims.

What is claimed is:

1. A deferred-action battery, comprising a cell casing, electrodes disposed in said casing, and electrolyte-supply means for feeding electrolyte into said casing and contact with said electrodes, said electrolyte-supply means including a housing forming an electrolyte chamber having an outlet; a substantially inflexible but incisable, generally planar diaphragm closing said outlet below the level of electrolyte in said chamber, said housing being formed with a compartment externally of said chamber communicating with said casing; a cutter pivotally mounted in said compartment adjacent said diaphragm for angular displacement about an axis generally parallel thereto, said cutter having a penetrating edge adapted to perforate said inflexible diaphragm upon forcible displacement in a predetermined sense about said axis; plunger means in said compartment engageable with said cutter for displacing it in said sense; precipitously triggerable actuating means for driving said plunger into engagement with said plunger means and said cutter into incising engagement with said diaphragm to release said electrolyte from said chamber; and pressure means establishing a pressure differential across said outlet for forcing said electrolyte out of said chamber through the incised diaphragm with operation of said actuating means.

2. A deferred-action battery, comprising a cell casing, electrodes disposed in said casing, and electrolyte-supply means for feeding electrolyte into said casing and contact with said electrodes, said electrolyte-supply means including a housing forming an electrolyte chamber having an outlet; a substantially inflexible but incisable, generally planar sheet-metal diaphragm closing said outlet below the level of electrolyte in said chamber, said housing being formed with a compartment externally of said chamber communicating with said casing; a cutter pivotally mounted in said compartment adjacent said diaphragm for angular displacement about an axis generally parallel thereto, said cutter having a penetrating edge adapted to perforate said inflexible sheet-metal diaphragm upon forcible displacement in a predetermined sense about said axis but normally restrained from displacement in said sense; plunger means in said compartment engageable with said cutter for displacing it in said sense; precipitously triggerable actuating means for driving said plunger into engagement with said plunger means and said cutter into incising engagement with said sheet-metal diaphragm to release said electrolyte from said chamber; and pressure means establishing a pressure differential across said outlet for forcing said electrolyte out of said chamber through the incised sheet-metal diaphragm with operation of said actuating means.

3. A deferred-action battery, comprising a cell casing, electrodes disposed in said casing, and electrolyte supply means for feeding electrolyte into said casing and contact with said electrodes, said electrolyte-supply means including a housing forming an elongated electrolyte chamber having an outlet at one end; a substantially inflexible but incisable, generally planar diaphragm closing said outlet below the level of electrolyte in said chamber, said housing being formed with a compartment externally of said chamber communicating with said casing; a cutter pivotally mounted in said compartment adjacent said diaphragm for angular displacement about an axis generally parallel thereto,

5 generally parallel thereto, said cutting having a penetrating edge adapted to perforate said inflexible diaphragm upon forcible displacement in a predetermined sense about said axis but normally restrained from displacement in said sense; plunger means in said compartment engageable with said cutter for displacing it in said sense; plunger means in said compartment engageable with said cutter for displacing it in said sense; precipitously triggerable actuating means for driving said plunger into engagement with said plunger means and said cutter into incising engagement with said diaphragm to release said electrolyte from said chamber; and pressure means establishing a pressure differential across said outlet for forcing said electrolyte out of said chamber through the incised diaphragm with operation of said actuating means, said pressure means including an inflatable bladder in said chamber, an inlet for a pressure fluid at an end of said chamber remote from said outlet communicating with said bladder; a source of pressure fluid supplying said inlet, normally closed valve means in said chamber at said inlet for blocking the supply of said pressure fluid from said source to said bladder prior to operation of said actuating means, and means for opening said valve means upon operation of said actuating means.

20 4. A deferred-action battery, comprising a cell casing, electrodes disposed in said casing, and electrolyte-supply means for feeding electrolyte into said casing and contact with said electrodes, said electrolyte-supply means including a housing forming an elongated electrolyte chamber having an outlet at one end; a substantially inflexible but incisable, generally planar sheet-metal diaphragm closing said outlet below the level of electrolyte in said chamber, said housing being formed with a compartment externally of said chamber communicating with said casing; a cutter pivotally mounted in said compartment adjacent said diaphragm for angular displacement about an axis generally parallel thereto, said cutter having a penetrating edge adapted to perforate said inflexible sheet-metal diaphragm upon forcible displacement in a predetermined sense about said axis but normally restrained from displacement in said sense; plunger means in said compartment engageable with said cutter for displacing it in said sense; precipitously triggerable actuating means for driving said plunger into engagement with said plunger means and said cutter into incising engagement with said sheet-metal diaphragm to release said electrolyte from said chamber; and pressure means establishing a pressure differential across said outlet for forcing said electrolyte out of said chamber through the incised sheet-metal diaphragm with operation of said actuating means, said pressure means including an inflatable bladder in said chamber, an inlet for a pressure fluid at an end of said chamber remote from said outlet communicating with said bladder, a source of pressure fluid supplying said inlet, normally closed valve means in said chamber at said inlet for blocking the supply of said pressure fluid from said source to said bladder prior to operation of said actuating means, and means for opening said valve means upon operation of said actuating means.

45 5. A deferred-action battery, comprising a cell casing, electrodes disposed in said casing, and electrolyte-supply means for feeding electrolyte into said casing and contact with said electrodes, said electrolyte-supply means including a housing forming an elongated electrolyte chamber having an outlet at one end; a substantially inflexible but incisable, generally planar sheet-metal diaphragm closing said outlet below the level of electrolyte in said chamber, said housing being formed with a compartment externally of said chamber communicating with said casing; a cutter pivotally mounted in said compartment adjacent said diaphragm for angular displacement about an axis generally parallel thereto, said cutter having a penetrating edge adapted to perforate said inflexible sheet-metal diaphragm upon forcible displacement in a predetermined sense about said axis but

normally restrained from displacement in said sense; plunger means in said compartment engageable with said cutter for displacing it in said sense; precipitously triggerable actuating means including an explosive squib co-operating with said plunger for driving it into engagement with said plunger means and said cutter into incising engagement with said sheet-metal diaphragm to release said electrolyte from said chamber; and pressure means establishing a pressure differential across said outlet for forcing said electrolyte out of said chamber through the incised sheet-metal diaphragm with operation of said actuating means, said pressure means including an inflatable bladder in said chamber, an inlet for a pressure fluid at an end of said chamber remote from said outlet communicating with said bladder, a source of pressure fluid supplying said inlet, normally closed valve means in said chamber at said inlet for blocking the supply of said pressure fluid from said source to said bladder prior to operation of said actuating means, and

means for operating said valve means upon operation of said actuating means.
